UNITED STATES PATENT OFFICE.

GUS GOODART, OF LATUDA, UTAH.

SWITCH-POINT CONNECTOR.

1,415,336.

Specification of Letters Patent. Patented May 9, 1922.

Application filed January 10, 1922. Serial No. 528,221.

To all whom it may concern:

Be it known that I, GUS GOODART, a citizen of United States, residing at Latuda, in the county of Carbon, State of Utah, have invented certain new and useful Improvements in Switch-Point Connectors; and I do hereby declare the following to be a full, clear, and exact description of the invention, such as will enable others skilled in the art 5 to which it appertains, to make and use the same.

This invention relates to new and useful improvements in railway devices and more particularly to switches.

15 One object of the invention is to provide a novel improved connecting device between a curve or main line rail and the switch point, the same being constructed and arranged to provide a strong and durable connection.

20 Another object of the invention is to provide a connector of this character which is formed in two parts and which must be moved beyond the operating angle of the switch point to permit disconnection.

25 Other objects and advantages will be apparent from the following description when taken in connection with the drawings.

In the drawings:

30 Figure 1 is a plan view of a portion of the railway showing the invention applied to the switch point.

Figure 2 is a side elevation of the same slightly enlarged.

35 Figure 3 is a bottom plan view.

Figure 4 is a sectional view taken on the line 4—4 of Figure 2.

Referring particularly to the accompanying drawing 10 represents a main line rail, 40 11 an adjacent curved rail, and 11' the switch point in connection with the latter, with which the invention is adapted for use and while the same is shown in connection with the curve rail, it may be used with equal 45 facility in connection with the main rail.

The connector comprises the two parts 12 and 13, the former of which has a rail tread portion 14, which aligns with the tread portion of the switch point 11', and has a pair 50 of parallel plates 15 extending longitudinally from one end and disposed on opposite sides of the web of the point 11', to which it is secured by means of bolts 16. One end of the portion 12 has a base flange 17 which 55 aligns with the base flange of the rail 11', the other end of the member 12 being cut

away in its under face to form the two reductions in thickness, as indicated at 18 and 19 respectively, thus producing a step joint. The adjacent vertical end face of the flange 60 17 is cut on an arcuate line transversely of the rail.

The other member 13 is disposed beneath the portion 18 and has a pair of parallel plates 26 extending longitudinally from one 65 end and disposed on opposite sides of the rail web 11, similar to the plates 25 and secured by bolts 30. The member 13 is cut away to form a shoulder 20, which engages beneath the part 19 of the member 12. Carried by the lower face of the portion 18, and extending downwardly therefrom is a pin 21, the lower end of which is formed with a radially extending web 22. Formed vertically through the member 13 is an opening 70 23, and formed longitudinally in the wall of the opening is a groove or channel 24, this web 22 and channel 24 being so positioned that they align when the members 12 and 13 are disposed at right angles to each other. 80 The web 22 may then enter the channel 24, and the parts are then assembled by pushing the pin 21 through the opening 23 until the upper edge face of the web 22 is disposed below the upper wall of the larger 85 lower end portion 25 of the opening 23. The members 12 and 13 are then swung so that the plates 15 of the former and the corresponding plates 26, of the latter, extend longitudinally in opposite directions. The 90 member 13 is formed with a base flange 27 having notches 28 in its edge faces for passage of spikes to secure the said member 13 to a tie. The inner edge face of the member 13 is cut on an arcuate line 29 to permit 95 the member to rotate on the pin 21 within the curved portion of the flange 17. The plates 26 straddle the web of the rail 11 and are secured thereto by bolts 30.

The operating movement of the switch 100 tongue together with the member 13, will be so slight, that the web 22 will not be brought into alignment with the channel 24, thus effectively preventing disengagement of the members 12 and 13.

105 This device is especially designed for use in connection with the switch point or "latches" of mine railways, but may be readily adapted for use in connection with other railways.

110 What is claimed is:

A switch point connector comprising a

pair of pivotally connected members having a scarf joint connection, one of the members having a vertical opening, the lower portion of which is enlarged to produce a shoulder, 5 the opening having a channel in its side wall, means carried by the members for connection respectively with a rail and a switch point, and a pin carried by the other member rotatably disposed in the opening of the 10 first member and having a transverse web

movable through the channel of the said opening and normally engaging beneath the shoulder of the said opening.

In testimony whereof, I affix my signature, in the presence of two witnesses.

GUS GOODART.

Witnesses:

E. N. RADCLIFF,
Geo. A. SCHULTZ.
